Primary Examiner — Rhea Shields(74) *Attorney, Agent, or Firm* — Birch, Stewart, Kolasch & Birch, LLP.(57) **CLAIM**

The ornamental design for an optical device, as shown and described.

DESCRIPTION

FIG. 1 is a top view of an optical device showing our new design;

FIG. 2 is a bottom view thereof;

FIG. 3 is a right side view thereof;

FIG. 4 is a left side view thereof;

FIG. 5 is a front view thereof;

FIG. 6 is a rear view thereof; and,

FIG. 7 is a perspective view thereof.

In the drawings, the broken lines are for the purpose of illustrating portions of the optical device that forms no part of the claimed design.
